No. 845,069.

PATENTED FEB. 26, 1907.

W. FEHR.
METAL BENDING MACHINE.
APPLICATION FILED NOV. 21, 1906.

UNITED STATES PATENT OFFICE.

WILLIAM FEHR, OF PHILADELPHIA, PENNSYLVANIA.

METAL-BENDING MACHINE.

No. 845,069.

Specification of Letters Patent.

Patented Feb. 26, 1907.

Original application filed December 22, 1905, Serial No. 292,946. Divided and this application filed November 21, 1906. Serial No. 344,449.

To all whom it may concern:

Be it known that I, WILLIAM FEHR, a citizen of the United States, residing at the city of Philadelphia, in the county of Philadelphia and State of Pennsylvania, have invented certain new and useful Improvements in Metal-Bending Machines, of which the following is a specification.

My invention has relation to a metal-bending machine; and in such connection it relates particularly to the construction and arrangement of such a machine and being a division of an application filed by me under date of December 22, 1905, Serial No. 292,946.

The principal objects of my invention are, first, to provide a bending-machine with means for bending the slotted portion of a metal strip designed to become a heddle 20 outward and in opposite directions to each other; second, to provide such a machine with movable dies adapted to permit of the automatic adjustment of the same to a position corresponding to the position of the 25 slotted portion in the strip; third, to provide one of the dies with projecting means which by passing through the slot of the metal strip and into a slot of the other die to permit the strip to automatically shift both 30 dies into a position in alinement with the slot in the strip when the same differs in its position with the position occupied by the dies; fourth, to arrange the means projecting from one of the dies movably therein so 35 as to permit of the shifting of the same back into the die by the metal strip when an unslotted portion of the same is shifted below the dies; and, fifth, to provide the dies with means to automatically return the same to 40 their normal operative position.

The nature and scope of my invention will be more fully understood from the following description, taken in connection with the accompanying drawings, forming part hereof, in which—

Figures 1 and 2 are views illustrating, respectively, in front and side elevations a machine having dies for bending certain portions of a metal strip in opposite directions, 50 means projecting from one of the dies for permitting of the shifting of both dies by the strip to be bent, and means for automatically returning the dies to their normal position, all embodying features of my invention. 55 Figs. 3 and 4 are detail views, enlarged, illus-

trating, respectively, in longitudinal and in cross-section the forming-dies and their holders. Fig. 5 is an enlarged horizontal sectional view of the upper forming-die and its holder. Fig. 6 is an enlarged top or plan view of the lower forming-die and its holder. Figs. 7 and 8 are detail views, enlarged, illustrating, respectively, in side elevation and in vertical section the upper forming-die. Figs. 9, 10, and 11 are similar views illustrating, respectively, in side elevation, top or plan view, and in vertical section the lower forming-die. Figs. 12 and 13 are views illustrating, respectively, in top or plan view and in side elevation a portion of the metal strip prior to 70 and after the bending of the same to complete the formation of an eye therein.

Referring to the drawings, k is a standard, having an opening k' , in which are arranged superposed dies k^2 and k^3 . The lower die k^2 proper is provided with a slot k^4 and with a depression k^5 and a projection k^6 at its upper face, as shown in Figs. 9, 10, and 11. The upper die k^3 proper consists of a U-shaped frame k^7 , having movably arranged therein a tapering blade k^8 , which by the intervention of a spring k^9 , engaging the base k^{10} and surrounding a stem k^{11} thereof, is normally held in a position in which the same projects a certain distance beyond the die k . At its lower face and at the respective sides of the blade k^8 the upper die k^3 is provided with a depression k^{12} and a projection k^{13} , similar in outline to the depression and projection of the lower die k^2 , but reversed in their arrangement, so as to permit of the engagement of the projection of one die in the depression of the other die, as will be readily understood in conjunction with Figs. 7 to 11, inclusive. The lower die k^2 is secured to a block k^{14} , 95 which is slidably arranged in a holder k^{15} and is held in proper position therein by springs k^{16} , engaging the block k^{14} from opposite sides, as shown in Fig. 6. The holder k^{15} is provided with arms k^{17} , adjustably supporting guide-screws k^{18} , between which a metal strip b , designed to become a heddle, passes and which serves to hold the same in proper position between the dies k^2 and k^3 , as shown in Fig. 3. The U-shaped upper die k^3 , by means of a set-screw k^{19} , is secured to a block k^{20} , slidably supported in a holder k^{21} by plates k^{22} , and is held in proper position by a spring, k^{23} secured to the holder k^{21} , as shown in Fig. 5. The holder k^{15} for the 110

lower die k^2 , by means of a bolt l and projections k^{24} , engaging the same from opposite sides, is adjustably secured to the standard k . At its lower end the die-holder k^{15} rests 5 upon a threaded bolt l' , arranged in a boss k^{25} of the standard k , which serves to adjust the lower die k^2 in a vertical plane in the standard k . The holder k^{21} for the upper die k^3 , by means of a bolt l^2 and ribs l^3 , is 10 secured to a slide l^4 , arranged in the standard k , and by the intervention of a bolt l^5 of a boss l^6 can be adjusted in a vertical plane on the slide l^4 . A block l^7 , pivotally secured to a bolt l^8 of the slide l^4 , is engaged 15 by a lever l^9 , pivotally secured in the point l^{10} to the standard k , which by means of an arm l^{11} , surrounding with its free end a roller on the driving-shaft a' , is connected with a cam a^8 thereof.

20 At each revolution of the driving-shaft a' the throw portion a^9 of the cam a^8 , by means of a roller l^{12} , secured to the arm l^{11} , will actuate the same and lever l^9 to depress the slide l^4 in the standard k , and thus bring the 25 upper die k^3 into engagement with the lower die k^2 . During the downward movement of the upper die k^3 the blade k^8 is first brought into engagement with the lower die k^2 by entering the slot k^4 thereof, after which the 30 projections k^6 and k^{13} will be brought into engagement with the shanks b^9 and b^{10} , formed by a slot b^2 , punched in the metal strip b , and will force the same into the depressions k^5 and k^{12} of the dies. The shanks b^9 and b^{10} of 35 the metal strip occupying the position shown in Fig. 12 will be bent in opposite directions, as shown in Fig. 13, thus forming an eye b^2 in the metal strip, which when serving as a heddle will be of a shape required to support 40 a thread. (Not shown.) In case the eye b^2 in the metal strip b does not occupy the proper position with respect to the dies k^2 and k^3 the same will automatically be brought into a position in alinement with the eye b^2 in 45 the strip b in the following manner: The blade k^8 of the upper die k^3 will with its pointed end first be brought into engagement with the slot b^2 of the strip b , and by descending into the same one of its inclined 50 sides will contact with one or the other of the end portions b^3 and be shifted sidewise by the strip b . This movement imparted to the blade k^8 is transmitted by the same to the upper die k^3 and to the lower die k^2 by descending into the slot k^4 thereof. The dies 55 k^2 and k^3 are thus moved sidewise in the holders k^{15} and k^{21} against the tension of their respective springs k^{16} and k^{23} and are held in this position until the shanks b^9 and 60 b^{10} of the metal strip are bent in the form shown in Fig. 13. As soon as the upper die k^3 is raised and its blades k^8 disengaged from the lower die k^2 and the metal strip b the springs k^{16} and k^{23} return the same to their 65 normal position in the respective holders k^{15}

and k^{21} . If, on the other hand, the metal strip should be so shifted that its slot b^2 is beyond the reach of the blade k^8 of the upper die k^3 or a slot should not have been punched therein, the same by abutting against the metal strip b will be moved backward into an inoperative position in the die k^3 against the tension of the spring k^{16} , bearing with its upper end against the block k^{20} , and will thus be prevented from being broken during the downward movement of the die k^3 .

Having thus described the nature and objects of my invention, what I claim as new, and desire to secure by Letters Patent, is—

1. In a machine of the character described, 80 dies, each of said dies having a projection and a depression, said dies when moved one against the other adapted to bend in opposite directions separated portions of a metal strip placed between the same, and means 85 carried by one of said dies adapted to engage the other of said dies prior to the bending of the metal strip by the depressions and projections thereof.

2. In a machine of the character described, 90 dies, each of said dies having a projection and a depression, said dies when moved one against the other adapted to bend in opposite directions separated portions of a metal strip placed between the same, and means 95 carried by one of said dies adapted to engage the other of said dies prior to the bending of the metal strip by the depressions and projections thereof, by first passing through a slot arranged in the strip.

3. In a machine of the character described, 100 dies, each of said dies having a projection and a depression reversed in position with respect to each other, means carried by the upper one of said dies, said means adapted 105 when said die is moved toward the lower one of the dies to engage a metal strip passing between the same and to be shifted into an inoperative position in the upper die, when abutting against an unslotted portion of 110 the strip.

4. In a machine of the character described, 115 holders, dies slidably arranged therein having means adapted to bend separated portions of a metal strip in opposite directions to form an eye therein, means extending from the upper one of said dies adapted to enter a slot arranged in the lower one of said dies, said extending means arranged when entering a slot of the metal strip to shift and hold both dies in alinement with the slot when the same differs in its position in the strip with the position occupied by the dies, and means for automatically returning said dies to proper position in their respective 120 holders, when disengaged by said extending means.

5. In a machine of the character described, 125 holders, dies slidably arranged therein having projections and depressions adapted to 130

- form eyes in a metal strip by bending separated portions thereof, in opposite directions to each other, a blade movably arranged in and extending from the upper one of said dies, means for returning said blade to an operative position in its die, when removed therefrom, said blade adapted to enter a slot arranged in the lower one of said dies and a slot in the metal strip placed between the dies 5 so as to be shifted by the strip to move the upper and lower die into alinement with each other and with the slot of the strip, when the said slot occupies a position sidewise to the central axis of said dies.
- 15 6. In a machine of the character described, holders, dies slidably arranged therein having projections and depressions adapted to form eyes in a metal strip placed between the same by bending separated portions thereof 20 in opposite directions to each other, a blade movably arranged in and extending from the
- upper one of said dies, means for returning said blade in an operative position in its die, when removed therefrom, said blade adapted to enter a slot arranged in the lower one 25 of said dies and to pass through a slot in the metal strip so as to be shifted by the strip to move the upper and lower dies into alinement with each other and with the slot of the strip when the said slot occupies a position 30 sidewise to the central axis of said dies and to shift said blade into an inoperative position, when an unslotted portion of the strip contacts with the same.
- In witness whereof I have hereunto affixed 35 my signature in the presence of the two subscribing witnesses.
